UNITED STATES PATENT OFFICE.

VLADIMIR SCHEWELIN, OF MOSCOW, RUSSIA.

APPARATUS FOR DRAWING FIBERS.

1,181,928.

Specification of Letters Patent.

Patented May 2, 1916.

Application filed August 6, 1912. Serial No. 713,618.

To all whom it may concern:

Be it known that I, VLADIMIR SCHEWELIN, a subject of the Emperor of Russia, residing at Moscow, Russia, have invented
5 certain new and useful Improvements in Apparatus for Drawing Fibers, of which the following is a specification.

The so-called cotton, woolen and other wastes, form a textile material, the fibers 10 of which are not only merely of short staple in comparison with the natural characteristic length of same, but also vary in length.

The method of producing the sliver, the unequal length of the fibers forming the 15 sliver, and the lack of adaptability in the drawing frames, preclude the possibility of drawing the sliver to the extent commensurate with the properties of the fibers under treatment. If the drawing of the slubbing be increased, the yarn either breaks or else thin distorted places or faults are 20 formed therein, these faults becoming the more noticeable as the difference between the length of the fibers forming the lap increases, that is to say, the less uniform the 25 length of the fibers in the lap. When flax fibers are (dry) spun in waste frames intended for spinning cotton fibers, the irregularity and imperfection of the yarn in 30 the sense referred to are still further intensified, and at the same time other circumstances adversely affecting the spinning process arise, in consequence of the special properties of the flax. Thus, it has been 35 found impracticable to make a No. 3 (English system of numbering) yarn from fine (chemically improved) flax fibers on a Platt waste-spinning frame, even in an irregular condition. On the other hand the applicant 40 has succeeded in producing a higher count than No. 16 of sufficient evenness, from lap of the same kind and in the same machine. This favorable result is obtained by means 45 of a new type of drawing frame, based on an improved principle of draft which the applicant has devised.

The drawing frames hitherto known (for dry spinning) are intended for drawing sliver composed of uniformly long fibers. 50 The distance between the points at which two adjacent pairs of drawing rollers grip the sliver for the purpose of drawing same, corresponds to the length of the fibers in the sliver, or is a little greater than same. 55 The resistance offered by the sliver or slubbing to the action of drawing at different

sections of its length does not vary to any considerable extent and is more or less uniform, so that the drawing of such a sliver or slubbing can be effected with corresponding regularity. The case is however, different with the more or less twisted slubbing produced in machines for treating waste. This material forms a mixture, in varying proportions, of cotton fibers $\frac{7}{8}$ to $\frac{1}{4}$ the normal length, whereas flax slubbing from the same machine consists of fibers 5.25 cm. to .75 cm. long; and in both cases the individual fibers no longer occupy a mutually parallel position. The resistance offered by this waste slubbing varies considerably in the different sections since the thicker portions contain a very large quantity of very short fibers which offer a very low resistance to drawing. Such a composition and the characteristic properties of the waste slubbing—especially when consisting of short flax fibers—prevent a more or less regular yarn of any higher count than No. 8 from being produced in drawing frames of known types.

In order to obtain better and more reliable results in making yarn from a slubbing or sliver consisting of fibers of irregular length, the applicant has invented (a) a new process or system of drawing the sliver or slubbing, and which forms the subject of a separate application for United States Letters Patent and (b) new types of drawing apparatus for carrying out the process. The present invention is concerned only with the types of drawing frames for carrying out the new process.

To enable the invention to be fully understood it is necessary to describe the new process, which presents the following characteristics: The sliver from the waste machines or from machines which treat fibers of the characteristic typical length or a slubbing—dependent of the composition of same—of fibers of equal or unequal length mixed in any proportions, is subjected to a continuous drawing action on the smallest possible sections of its length, so that the distances between the points at which the sliver or slubbing is gripped for the purpose of drawing shall be as small as possible, or at any rate, contrary to the general rule, shorter than the length of the fibers under treatment, provided the sliver or slubbing consists of fibers of equal length, and shorter than the lengths of the

shorter or predominating fibers in the sliver or slubbing, in the event of the fibers being of unequal length; in the apparatus constructed according to the present invention the material is held against the surfaces of the feed and drawing rollers by means of a yieldable gripping device or clamp consisting of at least two rollers of a small diameter less than that of the feed or drawing rollers, said device being an independent portion of the machine and capable of removal without dismantling the drawing machine. These small diameter rollers are interchangeably mounted and are provided with adjustable yielding springs for altering the pressure exerted on the material. The feed and drawing rollers or one of them are covered with an elastic material and auxiliary pressure rollers may be used 10 to press the material upon the feed and drawing rollers and may be combined with the clamping devices. By employing rollers of different diameters in the clamping device and adjusting the space between them 15 the length of material upon which the drawing action actually takes place may be varied and may be made extremely short. The most effective length of section over which the drawing should take place is determined 20 by the length of the fibers under treatment and the material of the surface of the rollers, the apparatus being adjusted accordingly. This system of holding the sliver or slubbing does not prevent the fibers 25 from slipping inside the same, and therefore the longer fibers, the length of which is greater than the length of the section under pressure, can be drawn without being broken, and thus form as it were the 30 axis or core of the yarn; by holding the sliver or slubbing at both ends in the manner described over a certain sectional length of same, and by drawing it in short sectional lengths, a more complete straightening 35 of the fibers is attained, the parallelism of the fibers, which was impaired during the doubling process or destroyed during carding or condensing at the same time being restored. The co-efficient of draft, that 40 is to say the ratio of the difference between the final length of the drawn slubbing and the original length of same (before the drawing commenced), may be distributed uniformly over all the drawings, or is reduced 45 in each successive drawing.

Figures 1, 2 and 3 show diagrammatically suitable apparatus for carrying out the process according to this invention. Fig. 4 is a plan view, and Fig. 5 is a front view 50 of one form of drawing frame adapted to be arranged as shown in either Figs. 1 or 2. Figs. 6 and 7 are details of same and Fig. 8 is a side view. Fig. 9 is a front view and Fig. 10 is a side view of one form of drawing frame arranged as shown in Fig. 3.

Fig. 11 shows a detail of same. Fig. 12 is a part sectional side view and Figs. 13 and 14 are plan views of a device for use with mule and self acting frames, enabling various operations to be carried out according 70 to the present invention.

In these drawings the arrangement according to the first type (Fig. 1) consists of two or more rollers 1¹, 1² to which a rotary motion in one and the same direction 75 is imparted by any known means. The cylindrical surfaces of the rollers are made of india rubber, leather, or other materials capable of producing great friction. The rollers are rotated in the direction indicated 80 by the arrows in Fig. 1, then the roller 1¹ serves to feed the sliver or slubbing and the roller 1² to deliver the same. A higher peripheral velocity is imparted to the roller 1² than to the roller 1¹, and therefore when 85 the rollers 1¹, 1² are rotated the sliver or slubbing arranged in accordance with Fig. 1, will move in the corresponding direction, and in passing from the surface of the roller 1¹, to that of the roller 1² will be subjected 90 to an increased velocity, that is to say a drawing so soon as the lap applies itself closely to the surface of the rollers 1¹, 1². The material is held against these surfaces by the pressure of the rollers 6, 7 which 95 revolve freely and form a gripping or clamping device. A free space of 1 to 2 mm. is left between the surfaces of the rollers 6, 7. In drawing a slubbing of cotton, flax waste, or other usual material a diameter of 3 to 5 100 mm. is chosen for the rollers 6 and 7, whereas in the case of drawing frames for cotton the diameter is 5 to 12 mm. In treating other material these dimensions depend on the length of the fibers in question. The 105 diameter of these clamping rollers 6 and 7 together with the size of the space between them determines the extent or sectional length over which the drawing action is exerted on the sliver or slubbing. With a 110 diameter of 3 mm. for the rollers 6, 7 and a space of 1 mm. between them, the draft affects a length of 4—5 mm. of the material. The rollers 11, 12, 13 . . . serve to press 115 the sliver or slubbing against the surface of the rollers 1¹, 1². A larger number of rollers may also be used for this purpose, the smaller number of same being located on the side of the roller 6 and the larger number on that of the roller 7. Further, a 120 roller 3 under which the slubbing or sliver is introduced through an eye 5 presses upon the roller 1¹. The axes 2¹, 2² of the rollers 1¹ and 1² can be moved closer together or separated, so as to enable the rollers 6 and 125 7 to be adjusted to the desired distance from the line *a b* connecting the axes 2¹, 2² without interrupting the pressure. If the material issuing from the last roller, *e. g.* 13, 130 is to be twisted, the spindle, or device for

that purpose, must be adjusted in such a manner that the yarn 14 forms a continuation of the tangent at right angles to the line *c d* connecting the centers of the axes 5 of the roller 1¹ and of the pressure roller 13. If the material is to be drawn again, the apparatus described is provided with another roller 1³, with axis 2³, and also a set of rollers 6', 7', 11', 12', 13' the arrangement 10 and functions of which are identical with those of the rollers 6, 7, 11, 12 and 13. The slubbing or sliver from the surface of the roller 1¹ is led under the rollers 11', 6', 7', 12' and 13' and is then subjected to twisting. 15 The roller 1³ receives a greater peripheral velocity than the roller 1¹.

The second type of drawing apparatus (Fig. 2) represents a modification of the first one. The rollers 1¹ and 1² and the 20 rollers 6² 7² 11² 12² 13² and 3² have functions similar to those of the corresponding rollers of the first type. The difference consists in (1) that the rollers 1¹, 1² are rotated in mutually opposite directions (the one for 25 instance, clockwise and the other anti-clockwise), (2) that the rollers 11² and 6² press the material against the surface of the roller 1¹, on one side of the line *a b* connecting the axes 2¹, 2², while the rollers 7², 12², 13² 30 press said material against the surface of the roller 1² on the other side of the same line.

The third type of drawing apparatus, Fig. 3, consists of a single drawing roller 1⁴ and a clamping device comprising a plate 6³ having two rollers 7³, 11 of small diameter thereon. The roller 7³ is adapted to press the sliver or slubbing 14 against the surface of the roller 1⁴, the roller 11 pressing said 40 material against the plate 6³. Auxiliary pressure rollers 12³, 13³ are provided as shown. When the roller 1⁴ is turned, for example in a clockwise direction, the material 1⁴ moves in the direction of the arrow and 45 passes through the eye 5³ and then over the surface of the plate 6³ which is arranged over the roller 1⁴ in such a manner that the entering end of the material 14 is approximately parallel to the line connecting the 50 centers of the first roller 7³ and roller 1⁴. The end of the plate does not extend quite up to the surface of the roller 1⁴. The material is drawn under the rollers 7³ and 12³, and in the event of the material 14 55 not being pressed against the surface of the plate 6³ by the roller 11, said material passes through without being drawn. Drawing begins as soon as the material 14 is pressed against the surface of the plate 6³ 60 by the roller 11. The drawing is effected on such portion of the material 14 as lies between the end of the plate 6³ and the point where it is gripped by the roller 7³. If the end of the plate be 1-1 $\frac{1}{2}$ mm. thick and the 65 diameter of the roller 7³ be 4 mm. the length

of material that will be subjected to the drawing action will be about 4 mm. The eye 5³ that is to say the opening for the passage of the material has a diameter corresponding to the thickness of said material. 70 Drawn into the eye 5³ by the drawing roller, the material traverses the same unless checked by any thickened portion, the drawing action however, causing said thickened portion to be drawn out until of a suitable 75 size to pass through the eye. Under the roller 11 the material is subjected to a similarly compensating action. Accordingly this third type of drawing apparatus acts as a regulator of the thickness of the material the diameter of the eye 5³ and the width of the space between the roller 11 and the surface 6³ acting as a gage for the lap. 80

Fig. 4 illustrates one form of drawing apparatus which can be adapted for use according to the types shown in Figs. 1 and 2. 85

The apparatus (Figs. 4, 5, 6, 7 and 8) consists of a casing 18⁵, on the longitudinal sides of which are situated side frames 19⁵ and 20⁵, with openings for the passage of 90 the shafts 2⁵, 2⁶ and flange pieces 24⁵, shaped as shown. Between the frames 19⁵ and 20⁵ are mounted a feed roller 1⁵, and a drawing roller 1⁶ adapted to rotate on the shafts 2⁵, 2⁶, by which they are carried. The surfaces 95 of these rollers are faced with a layer of elastic material 71 such as cloth, leather, rubber or the like, capable of producing a considerable amount of friction. The shafts of the rollers pass through the walls of the 100 casing 18⁵. If the drawing apparatus is to act as an independent machine, pinions of desired dimensions are mounted on the shafts 2⁵ and 2⁶ which pinions transmit the motive power to the apparatus. If, however, the apparatus merely forms part of a spinning frame, then its shafts are geared in any convenient manner with some rotating part of the spinning frame. The side frames 19⁵ and 20⁵ are provided with slots 110 23⁵, 23⁶, . . . in which are inserted the ends of the shafts of the clamping rollers 6⁵, 7⁵, and the auxiliary pressure rollers 11⁵, 12⁵, 13⁵. The said rollers have a diameter of 3 to 8 mm. Drawbars 25⁵, 25⁶ . . . are mounted on 115 both ends of the shaft of each roller, and pass through openings in the pieces 24⁵. The ends of the drawbars are provided with threads, above which are arranged spiral springs 22⁵, 22⁶ . . . and nuts 21⁵, 21⁶. By 120 tightening up the nuts the rollers are pressed against the surface of the feed and drawing rollers, the shafts 9⁵, 10⁵, 15⁵, 16⁵, 17⁵ sliding in slots 23⁵, 23⁶ . . . as in guides. These slots, are arranged above the peripheries of the 125 two drawing rollers and extend radially in the direction of the centers of the rollers as far as the periphery of the same as shown. When both the feed and drawing rollers revolve in the same direction for example 130

clockwise, the pressure and clamping rollers are located on the upper side of the feed and drawing roller, as is shown in Fig. 1, but if the feed and drawing rollers revolve 5 in opposite directions, then the clamping and pressure rollers 11⁵ and 6⁵ remain in their original position, while the rollers 7⁵, 12⁵, 13⁵ are transferred to slots arranged on the underside of the drawing roller 1⁶. The 10 frames 19⁵ and 20⁵ are surrounded by a fillet 28⁵ to which is secured a drawbar with an eye (or two eyes) 27⁵, through which the material is led under the rollers 11⁵, 6⁵, 7⁵, 12⁵, 13⁵, is passed. Since the distances 15 between the points of application of the pressure of the rollers 6⁵ and 7⁵ are smaller in the position represented in Fig. 1 than according to Fig. 2 it is thus possible, on one and the same apparatus, to treat a sliver or 20 slubbing both with very short fibers (when the rollers are arranged on the one side only) and with very long fibers (when the rollers are arranged on both sides).

The apparatus above described operates 25 in the following manner: The material is inserted in the eye 27⁵, and is then led under the rollers 11⁵, 6⁵, 7⁵, 12⁵, 13⁵. The drawing roller 1⁶ which runs at a higher peripheral velocity than the feed roller 1⁵ 30 exerts a drawing action on the material 14, which issues, in a drawn condition. The strength of the pressure with which the material is forced against the surface of the rollers 1⁵ and 1⁶, is adjusted and controlled 35 by means of the nuts 21⁵, 21⁵... With the rollers 11⁵, 6⁵, 7⁵, 12⁵, 13⁵ and the material arranged as shown in Fig. 1 and in consequence of the said rollers receiving their motion from the moving surfaces of the rollers 1⁵ and 1⁶ that side of the material which is in contact with the rollers 11⁵, 6⁵, 7⁵, 12⁵, 13⁵ is somewhat retarded in its movement 40 in comparison with the other side of the material which is carried forward by the surfaces of the rollers 1⁵, 1⁶, and which overruns the first side for the additional reason that it forms the exterior, "bending" side whereas the former constitutes the inner, "bent" side. In this way the material is 45 not merely subjected to a drawing action, but, in addition, the side next the drawing rollers is also caused to slip or overrun the side next the pressure rollers. Owing to 50 this circumstance the number of defective 55 thin distorted places is lessened.

Figs. 9, 10 and 11 illustrate one form of drawing apparatus of the third type according to this invention. This arrangement which enables a lap or sliver to be 55 drawn by means of a single drawing roller, consists of a casing 30, inside which is arranged, the drawing roller 31, the shaft 32 of which passes through openings in the long sides of the casing 30. The drawing 60 roller is faced with rubber, or some other

elastic material capable of generating considerable friction. If the apparatus is intended to act as a separate machine, a suitable member—such as a pinion or belt pulley—for receiving the motive power is 70 mounted on its shaft 32; but if the apparatus forms part of a combined spinning frame then the drawing roller is driven from said spinning frame in any suitable manner. The two long sides of the casing 30 are provided 75 with slots for holding a plate 33 carrying the clamping rollers 34, 35. The lower edge of the plate, which is preferably rounded off, has a thickness of $\frac{1}{2}$ mm. Instead of being rounded off the plate may have a 80 roller 35 mounted on the edge of same (see Fig. 11). The roller 35 is mounted in slots at the edge of the plate. Drawbars 36 provided with screw threads and with spiral springs 37, and nuts 38 are secured to the 85 plate 33. These drawbars pass through openings in the board 39 which is secured to the two long sides of the casing 30. By adjusting the nuts the plate 33 can be moved toward the surface of the drawing roller 31 90 similarly moving the roller 35. The surface of the roller 35 projects toward the side of the drawing roller 31 in such a manner that the thin end of the plate 33 cannot come in contact with the surface of the roller 95 31 when the roller 35 is pressed against the latter. Projections 40 are provided on the under part of the plate 33, between which projections is mounted, so as to be a little above the roller 35, the pressure roller 34. 100 The spindle of the pressure roller 41 is carried in slots 42 in the long sides of the casing. Drawbars 43 with nuts 44 and springs 45 therein are provided for adjusting the pressure of the roller 41, upon the surface 105 of the drawing roller 31. The projections 40, of the plate 33 are provided with grooves 46, in which is inserted a plate 47 provided with an opening for the passage of the sliver or slubbing 14. The plate 47 is changed in 110 accordance with the count of the slivers or slubbings to be treated. This drawing apparatus can act in two ways (a) for equalizing the thickness of the sliver or slubbing previous to drawing, and (b) directly for 115 the purpose of producing a moderate draft, while at the same time equalizing the thickness of the sliver or slubbing.

Figs. 12, 13 and 14 illustrate a device for use with mule and self-acting frames and 120 enabling various operations to be carried out in accordance with the present process. The shafts 48, 49 of the drawing rollers 50, 51 the surfaces of which are faced with elastic material, are mounted in the bearings 52, 53. The upper gripping or pressure rollers now in use are dispensed with, and are replaced by two to six rollers such as clamping rollers 54, 55, and a series of auxiliary pressure rollers 56, 57, 58, 59^a, (ac- 130

cording to the task to be performed) of smaller diameter and with corresponding shafts 59, 60, 61, 62, 63. These shafts are carried in yokes 64, 65 . . . (separate 5 yokes for each pair of shafts) to which are secured in any convenient manner rods 66 which pass through openings in each of the two top pieces 67. These top pieces 67 are secured to the frame or casing 68 in any 10 convenient manner. A rubber buffer or spiral spring 69, is placed in each of the openings in the top pieces 67, and a screw 70 bears upon same provided with lock nuts 71. By turning these screws the pressure 15 of the rollers 54, 55, 56, 57, 58 upon the surface of the rollers 50, 51 can be adjusted. In the present instance, as in all the drawing apparatus described above, the interposition of buffers or springs 69, is necessary 20 for obtaining a more uniform pressure of the rollers 54, 55, 56, 57, 58 against the elastic surface of the drawing rollers. The described type of drawing apparatus is intended for drawing either wet or dry 25 fibers of equal or unequal lengths from 10 to 30 mm. and in all said types the rollers are of the usual lengths. These types are intended for use, on the one hand, as component elements of spinning frames on a 30 manufacturing scale, and on the other hand as independent machines, in combination with spinning or twisting devices in home or other industries.

What I claim is:—

- 35 1. In apparatus for drawing fibrous material of short fibers of equal or unequal length, clamping means including a series of detachable yielding clamping devices for regulating the length of material over 40 which drawing action takes place, said devices being capable of removal without dismantling the machine.
2. In apparatus for drawing fibrous material of short fibers of equal or unequal 45 length, clamping means including two rollers forming detachable yieldable clamping devices for regulating the length of mate-

rial over which drawing action takes place, and means for regulating the pressure exerted by said clamping devices.

50

3. In apparatus for drawing fibrous material of short fibers of equal or unequal length, a feed roller, a drawing roller, sheathings of elastic material on said rollers, two rollers of a diameter less than that 55 of the feed and drawing rollers interchangeably mounted and forming a detachable clamping device for pressing the material against the surfaces of the feed and drawing rollers and means for regulating the 60 pressure exerted by said clamping device.

65

4. In apparatus for drawing fibrous material of short fibers of equal or unequal length, a feed roller, a drawing roller, sheathings of elastic material on said rollers, two rollers of a diameter less than that 65 of the feed and drawing rollers interchangeably mounted and forming a detachable clamping device for pressing the material against the surfaces of the feed and drawing 70 rollers, means for regulating the pressure exerted by said clamping device and an auxiliary pressure roller of small diameter also acting on the material.

70

5. In apparatus for drawing fibrous material of short fibers of equal or unequal length, a feed roller, a drawing roller, sheathings of elastic material on said rollers, two rollers of diameter less than that 80 of the feed and drawing rollers interchangeably mounted and forming a detachable clamping device for pressing the material against the surfaces of the feed and drawing rollers, draw bars carrying said small diameter rollers, adjustable springs on said 85 drawbars and auxiliary pressure rollers of small diameter also acting on the material.

In witness whereof I have hereunto set my hand in the presence of two subscribing witnesses.

WLADIMIR SCHEWELIN.
